a corporation of Missouri

Application March 25, 1937, Serial No. 68,401

Term of patent 14 years

To all whom it may concern:

Be it known that I, William A. Nester, a citizen of the United States, residing at East St. Louis, in the county of St. Clair and State of Illinois, have invented a new, original, and ornamental Design for a Bottle, of which the following is a specification, reference being had to the accompanying drawing, forming part thereof.

Fig. 1 is a rear view of a prescription bottle showing my design.

Fig. 2 is a front view of the bottle shown in Fig. 1.

Fig. 3 is a bottom view of the bottle shown in Fig. 1.

A characteristic feature of my novel design resides in the latticed panels, one of which lies at each side of the graduations. The lattice work is formed in the glass in the manner shown by Figs. 1 and 3.

I claim:

The ornamental design for a bottle, substantially as shown and described.

WILLIAM A. NESTER.
